United States Patent Office

Des. 192,163
Patented Feb. 6, 1962

192,163

TELEPHONE ENCLOSURE

Henry G. Turner, Atlanta, Ga., assignor to American Telephone and Telegraph Company, New York, N.Y., a corporation of New York

Filed Sept. 26, 1960, Ser. No. 62,259

Term of patent 14 years

(Cl. D13—1)

FIG. 2

FIG. 1

FIG. 1 is a front perspective view of a telephone enclosure showing my new design; and

FIG. 2 is an elevational view of the right-hand side of my new design for a telephone enclosure of which the opposite side is a mirror image.

The dominant features of the invention are shown in solid lines. The telephone and directory are shown in broken lines for illustrative purposes only.

I claim:

An ornamental design for a telephone enclosure, as shown and described.
